UNITED STATES PATENT OFFICE

108,594

DESIGN FOR A JAR

Walter L. Kennedy, Baltimore, Md., assignor to
Crosse and Blackwell Company, Baltimore,
Md., a corporation of Maryland

Application January 13, 1938, Serial No. 74,263

Term of patent 7 years

To all whom it may concern:

Be it known that I, Walter L. Kennedy, a British subject, residing at Baltimore, in the State of Maryland, have invented a new, original, and ornamental Design for a Jar, of which the following is a specification, reference being had to the accompanying drawing, forming a part thereof.

In the drawing:

Fig. 1 is a front elevational view of a jar showing my new design;

Fig. 2 is a side elevational view thereof; and
Fig. 3 is a sectional view taken along the line
3—3 of Fig. 1 to more clearly illustrate the sur-
face contour of the jar.

I claim:

The ornamental design for a jar substantially
as shown and described.

WALTER L. KENNEDY.
